HEATING OF FLUIDS

Marion W. Barnes, Chicago, Ill., assignor to Universal Oil Products Company, Chicago, Ill., a corporation of Delaware

Application September 2, 1933, Serial No. 687,956
Renewed January 5, 1935

14 Claims. (Cl. 196—110)

This invention refers to improvements in furnaces particularly suitable for heating hydrocarbon oils to the high temperatures required for their pyrolytic conversion and, more specifically, adapted to the conversion of relatively low-boiling hydrocarbon oils of the character requiring extended conversion time at a substantially constant temperature in the final stages of their heat treatment in order to produce maximum yields of desirable low-boiling products such as motor fuel of high antiknock value.

It is well known that many hydrocarbon oils of a relatively low-boiling character, such as kerosene or kerosene distillate, pressure distillate bottoms, naphtha, straight-run gasoline or other motor fuel of inferior antiknock value and the like, may be successfully converted for the production of high yields of motor fuel of good antiknock value by heating the oil to the desired conversion temperature and then maintaining the same at or near the temperature attained for a predetermined length of time in the final stages of the heating coil, without the necessity of employing a high pressure reaction vessel for separation of the vaporous and liquid conversion products and continued conversion of the vapors. The present invention offers a simple and efficient heating means whereby this type of operation may be accomplished.

The present invention is, however, not limited to use in the conversion of hydrocarbon oils but will be found advantageous in any process involving the heating of any fluid wherein a heating curve of the general character obtained by the apparatus of the present invention is desired.

One specific embodiment of the apparatus of the present invention may comprise a main furnace structure having side walls, end walls, a roof and a floor, a combustion zone within said structure, a convection heating zone separated from said combustion zone but in communication therewith, means for supplying combustibles to said combustion zone, means for removing combustion gases from said convection zone, a fluid conduit comprising a plurality of tubular elements in said convection heating zone, a fluid conduit comprising an exposed and a shielded row of tubular elements disposed along the roof of the furnace and adjacent the convection heating zone, a fluid conduit comprising a plurality of tubular elements adjacent the floor of the combustion zone and a fluid conduit comprising an exposed and a shielded row of tubular elements adjacent the roof of the combustion zone, means for passing a fluid to be heated through

adjacent tubes in each fluid conduit in series and means for passing the fluid in series through the various fluid conduits in the order above given.

The accompanying diagrammatic drawing and the following description thereof will serve to more clearly illustrate the features and advantages of the present invention.

Fig. 1 of the drawing is a cross-sectional elevation of one specific form of furnace embodying the features of the present invention.

Fig. 2 illustrates the general type of heating curve obtainable in the furnace shown.

Referring in detail to the drawing and particularly to Fig. 1, the front and rear end walls of the main furnace structure are indicated, respectively, by reference numerals 1 and 2, 3 is the roof and 4 the floor. Side wall 5 is shown in elevation and the similar opposite side wall is not shown, due to the view being taken in section. A bridge wall 6 separates combustion zone 7 from the convection heating zone 8.

In the embodiment here illustrated, combustible fuel of any desired form is supplied, together with all or a regulated portion of the air required for combustion, to combustion zone 7 through one or a plurality of similar firing tunnels 9 by means of a burner or burners of any desired form, not shown. Additional air for combustion or auxiliary air may be supplied to combustion zone 7 through air ducts 10 controlled by dampers 11 disposed adjacent firing tunnel 9 and within the same general structure. Preferably a plurality of similar firing tunnels and air ducts are employed, positioned along the lower portion of front wall 1 of the furnace in order to secure a uniform distribution of combustibles to combustion zone 7. Only a single firing tunnel is seen in the particular view of the furnace here illustrated. Combustion gases pass from combustion zone 7 over bridge wall 6, downwardly through the convection heating zone 8 and out of the furnace through flue 12 to a suitable stack, not shown.

A fluid conduit or tube bank 13 is positioned within convection heating zone 8 and comprises, in the embodiment illustrated, a plurality of parallel rows of horizontally disposed tubes 14. Adjacent tubes in the same row and at the ends of adjacent rows are connected at their ends in series by means of suitable headers or return bends, not illustrated in the drawing. The connections between the tubes at their rear ends are indicated diagrammatically by the lines 15.

Another bank of tubes or fluid conduits 16, comprising two parallel rows of horizontally dis-

posed tubes 14, is positioned along the roof 3 of the furnace adjacent the convection zone 8. Adjacent tubes in alternate rows of this bank are connected at their ends in series, as indicated, diagrammatically by the lines 15 at the rear ends of the tubes.

Another tube bank or fluid conduit 17 comprising a single row of horizontally disposed tubes 14, is positioned adjacent the floor of the combustion zone and adjacent tubes in this bank are connected at their ends in series, as indicated diagrammatically by the lines 15.

Another bank of tubes or fluid conduit 18 comprising an exposed and a shielded row of horizontally disposed tubes 14, is positioned adjacent the roof of the combustion zone. Adjacent tubes in the same row of this bank are connected at their ends in series, as indicated diagrammatically by the lines 15, and, in the embodiment illustrated, the two rows of tubes are connected in series, the flow through the shielded row being reverse to that through the exposed row.

The various tube banks 13, 16, 17, and 18 are preferably connected in series in the order given when the furnace is employed for the conversion of low-boiling hydrocarbon oils and, in the particular case here illustrated, the flow of oil, as indicated by the arrows, may be as follows: The oil enters an end tube in the lower row of bank 13, flowing through the adjacent tubes in each row and through the adjacent rows in series, the general direction of flow being upwardly through this bank countercurrent to the flow of combustion gases. The oil leaves an end tube in the top row of bank 13, passing through a cross-over line indicated diagrammatically at 19 into the end tube in the lower row of bank 16. The oil then passes into the end tube of the upper row of bank 16 and through adjacent tubes in alternate rows of this bank in series, emerging from the last tube in the opposite end of the bank and passing through cross-over line indicated diagrammatically at 20 into the end tube adjacent bridge wall 6 of bank 17. The oil flows through adjacent tubes in bank 17 in series and the general direction of flow in both banks 16 and 17 is, in the case illustrated, countercurrent to the direction of firing and to the general direction of flow of the combustion gases. The oil leaves the end tube of bank 17 adjacent the front of the furnace and is transferred through cross-over line indicated diagrammatically at 21 into the end tube adjacent the front of the furnace of the exposed row of bank 18. The oil then passes through adjacent tubes in the exposed row of bank 18 in series, concurrent to the direction of firing and general direction of flow of the combustion gases, is transferred from the end tube of bank 18 most adjacent bridge wall 6 into the last tube at the same end of the shielded row of bank 18, passing through adjacent tubes in this row in series countercurrent to the direction of firing and general direction of flow of the combustion gases, and finally emerging from the end tube of this row adjacent the front of the furnace through line 22 to subsequent cracking or the like equipment, not pertinent to the present invention and not here illustrated.

The general type of heating curve ordinarily obtained in a furnace such as illustrated with a flow of the general character described is indicated in Fig. 2 of the drawing. It will be noted with reference to this curve that the temperature of the oil is gradually raised as it passes through bank 13, as indicated by the slope of section

A of the curve. A more rapid rate of temperature rise is obtained in bank 16 as indicated in section B of the curve and a still more rapid rate is obtained in bank 17, as indicated by the slope of section C of the curve and the oil is maintained at a substantially constant temperature as it passes through bank 18, as indicated by section D of the curve. Primarily sensible heat is imparted to the oil in section A of the curve, corresponding to the time during which the oil passes through bank 13. Additional sensible heat and a large portion of the latent heat of vaporization is added to the oil in section B, corresponding to the time during which the oil passes through bank 16. Some of the latent heat of cracking may also be obtained in this section of the furnace. Substantially all of the remaining sensible heat imparted to the oil as well as the remaining latent heat of vaporization and a substantial proportion of the latent heat of cracking is imparted to the oil in section C of the curve, which represents the time in tube bank 17. Very little sensible heat but a large proportion of the latent heat of cracking is imparted to the oil in section D of the curve representing the time in tube bank 18.

It will be understood that many modifications of the specific form of furnace illustrated and described as well as minor departures from the specific flow illustrated and described may be employed within the scope of the present invention. For example, the general direction of flow through any or all of the various individual tube banks may be reversed, the sequence of flow through the various banks being maintained, however. Also parallel instead of series flow through all or a portion of the tubes in bank 13 may be employed, if desired, in order to decrease pressure drop, due to friction, through the heating coil. Another modification of the specific form of furnace and the flow illustrated and described, which is specifically within the scope of the present invention, comprises eliminating from the furnace that portion of tube bank 16 directly above bank 13, which portion is indicated at 23, in which case the flow of oil between tube bank 13 and 16 is as indicated diagrammatically by line 24.

It will be understood that the various modifications mentioned are not to be considered equivalent although they do not alter the general heating method employed nor the general type of heating curve obtained. For example, by eliminating section 23 of tube bank 16 a somewhat higher rate of heating than that indicated by the curve in Fig. 2 of the drawing will be obtained in bank 13, particularly in the upper two or three rows of this bank and the slope of section A of the curve in Fig. 2 will be somewhat more pronounced, for example as indicated by line A'.

Various other modifications of the specific form of furnace and the specific flow illustrated and described will be apparent to those skilled in the art and it is therefore not intended to limit the broad spirit and scope of the present invention except as defined in the appended claims.

I claim as my invention:

1. A furnace for heating hydrocarbon oils which comprises in combination, a main furnace structure having side walls, end walls, a roof and a floor, a combustion zone within said furnace structure, a separate convection heating zone in communication with said combustion zone, means for supplying combustibles to said

5 combustion zone, means for removing combustion gases from said convection zone, a fluid conduit within said convection heating zone, a fluid conduit disposed along the roof of the furnace adjacent said convection zone, a fluid conduit adjacent the floor of the combustion zone, a fluid conduit positioned adjacent the roof of the combustion zone and means for passing hydrocarbon oil through the various fluid conduits in the sequence above given.

10 2. A furnace for heating hydrocarbon oils which comprises in combination, a main furnace structure having side walls, end walls, a roof and a floor, a combustion zone within said furnace structure, a separate convection heating zone in communication with said combustion zone, means for supplying combustibles to said combustion zone, means for removing combustion gases from said convection zone, a fluid conduit within said convection heating zone, a fluid conduit disposed along the roof of the furnace adjacent said convection zone, a fluid conduit adjacent the floor of the combustion zone, a fluid conduit positioned adjacent the roof of the combustion zone and means for passing hydrocarbon oil in a continuous stream through the various fluid conduits in the sequence above given.

15 3. A furnace for heating hydrocarbon oils which comprises in combination, a main furnace structure having side walls, end walls, a roof and a floor, a combustion zone within said furnace structure, a separate convection heating zone in communication with said combustion zone, means for supplying combustibles to said combustion zone, means for removing combustion gases from said convection zone, a fluid conduit comprising a plurality of serially connected, horizontally disposed tubular elements positioned within said convection heating zone, a fluid conduit comprising a plurality of serially connected, horizontally disposed tubular elements disposed along the roof of the furnace adjacent said convection heating zone, a fluid conduit comprising a plurality of serially connected, horizontally disposed tubular elements positioned adjacent the roof of the combustion zone, and means for passing hydrocarbon oil in a continuous stream through the various fluid conduits in the sequence above given.

20 4. A furnace for heating hydrocarbon oils which comprises, in combination, a main furnace structure having side walls, end walls, a roof and a floor, a combustion zone within said furnace structure, a separate convection heating zone in communication with said combustion zone, means for supplying combustibles to said combustion zone, means for removing combustion gases from said convection zone, a fluid conduit comprising a plurality of superimposed horizontal rows of horizontally disposed tubular elements connected at their ends in series and positioned within said convection heating zone, a fluid conduit comprising two parallel horizontal rows of horizontally disposed tubular elements positioned along the roof of the furnace adjacent said combustion heating zone, adjacent tubes in alternate rows being connected at their ends in series, a fluid conduit comprising a single horizontal row of horizontally disposed tubular elements connected at their ends in series and positioned adjacent the floor of the combustion zone, a fluid conduit comprising an exposed horizontal row and a

shielded horizontal row of horizontally disposed tubular elements positioned adjacent the roof of the combustion zone, adjacent tubes in each row being connected at their ends in series and the two rows connected in series, and means for passing a continuous stream of hydrocarbon oil through the various fluid conduits in the sequence given.

5 5. A furnace for heating hydrocarbon oils which comprises in combination, a main furnace structure having side walls, end walls, a roof and a floor, a combustion zone within said furnace structure, a separate convection heating zone in communication with said combustion zone, means for supplying combustibles to said combustion zone, means for removing combustion gases from said convection zone, a fluid conduit comprising a plurality of superimposed horizontal rows of horizontally disposed tubular elements connected at their ends in series and positioned within said convection heating zone, a fluid conduit comprising two parallel horizontal rows of horizontally disposed tubular elements positioned along the roof of the furnace adjacent said combustion heating zone, adjacent tubes in alternate rows being connected at their ends in series, a fluid conduit comprising a single horizontal row of horizontally disposed tubular elements connected at their ends in series and positioned adjacent the floor of the combustion zone, a fluid conduit comprising an exposed horizontal row and a shielded horizontal row of horizontally disposed tubular elements positioned adjacent the roof of the combustion zone, adjacent tubes in each row being connected at their ends in series and the two rows connected in series, means for passing a continuous stream of hydrocarbon oil first through the first mentioned fluid conduit in a general direction countercurrent to the flow of combustion gases, then through the second mentioned fluid conduit in a general direction countercurrent to the flow of combustion gases, then through the third mentioned fluid conduit in a general direction countercurrent to the direction of firing, then through the exposed row of tubes in the last mentioned fluid conduit in a general direction concurrent to the direction of firing and finally through the shielded row of tubes in the last mentioned fluid conduit in a general direction countercurrent to the direction of firing.

10 6. In combination with a furnace having a combustion zone and a convection heating zone in communication with the combustion zone, means for firing the combustion zone at the end of the furnace opposite the convection zone, a bank of heating tubes in the convection zone, a second bank of tubes adjacent the furnace roof remote from the firing means and connected to the first named bank, a third bank of tubes adjacent the floor of the combustion zone and connected to said second bank, and another bank of tubes connected to said third bank and positioned adjacent the furnace roof closer to the firing means than said second bank.

15 7. The combination as defined in claim 6 further characterized in that said second bank of tubes is positioned partially in the combustion zone and in part directly over the first-named bank.

20 8. A furnace comprising a combustion zone, a convection heating zone at one end of the furnace and in communication with the combustion zone, means for firing the combustion zone at the opposite end of the furnace toward the convection zone, a bank of heating tubes in the con-

- vection zone, a second tube bank adjacent the furnace roof and having a plurality of tubes positioned in the combustion zone remote from the firing means, a third tube bank adjacent the floor of the combustion zone, and another tube bank adjacent the roof of the combustion zone closer to the firing means than said second bank, and means for passing fluid to be heated serially through said banks in the order named.
9. A furnace comprising a combustion zone having roof tubes and floor tubes, means for firing the furnace at one end of the combustion zone, a convection heating zone communicating with the opposite end of the combustion zone, heating tubes in the convection zone, and means for passing fluid to be heated first through the last named tubes, then through a portion of the roof tubes remote from the firing means, then through the floor tubes and finally through the remaining portion of the roof tubes closer to the firing means.
10. In a furnace having roof tubes, floor tubes, firing means at one end and convection tubes at the opposite end thereof, the combination of means for passing fluid to be heated first through the convection tubes, then through a portion of the roof tubes remote from the firing means, then through the floor tubes and finally through the remaining portion of the roof tubes closer to the firing means.
11. In a furnace for heating fluids, the combination of a pair of fluid conduits each comprising two parallel horizontal rows of horizontally disposed heating tubes positioned adjacent the roof of the furnace, adjacent tubes in alternate

rows of one of the conduits being connected at their ends in series, and adjacent tubes in each row of the other conduit being connected at their ends in series and the two rows of this conduit being connected in series, and means for passing a fluid to be heated through both rows of one of said conduits and subsequently through both rows of the other of said conduits.

12. In a furnace for heating fluids, the combination of a fluid conduit comprising two parallel horizontal rows of horizontally disposed heating tubes positioned adjacent the roof of the furnace, adjacent tubes in the alternate rows being connected at their ends in series, a second fluid conduit comprising two rows of horizontal heating tubes, the last-named rows being connected in series with each other and disposed in the furnace in horizontal alignment with the rows of the first-named conduit and adjacent tubes of each of said last-named rows being connected at their ends in series, and means for passing a fluid to be heated through both rows of one of said conduits and subsequently through both rows of the other of said conduits.

13. The combination as defined in claim 11 further characterized in that said means comprises a horizontal row of heating tubes positioned adjacent the floor of the furnace and connected between said conduits.

14. The combination as defined in claim 12 further characterized in that said means comprises a horizontal row of heating tubes positioned adjacent the floor of the furnace and connected between said conduits.

MARION W. BARNES. 35
